UNITED STATES PATENT OFFICE.

JOSEPH A. SCHERTZ, OF MARQUETTE, NEBRASKA.

DESIGN FOR A COMBINATION WIRE STRETCHER AND CUTTER.

43,747.

Specification for Design.

Patented Mar. 25, 1913.

Application filed November 11, 1912. Serial No. 730,818. Term of patent 7 years.

To all whom it may concern:

Be it known that I, JOSEPH A. SCHERTZ, a citizen of the United States, residing at Marquette, in the county of Hamilton and State of Nebraska, have invented a new, original, and ornamental Design for a Combination Wire Stretcher and Cutter, of which the following is a specification, reference being had to the accompanying drawing, forming a part thereof.

Figure 1 is a side view of a combination wire stretcher and cutter, showing my new

design. Fig. 2 is a plan view of the combination wire stretcher and cutter. Fig. 3 is an end view of the same.

I claim:

The ornamental design for a combination wire stretcher and cutter, as shown.

In testimony whereof I have affixed my signature in presence of two witnesses.

JOSEPH A. SCHERTZ.

Witnesses:

LETTIE HISCOCK,
H. A. JOHNSON.
